UNITED STATES PATENT OFFICE

151,305

DESIGN FOR A PUSH BUTTON

Chauncey E. Waltman, Chicago, Ill., assignor to
Nutone, Incorporated, Chicago, Ill., a corpora-
tion of New York

Application January 16, 1947, Serial No. 136,184

Term of patent 3½ years

(CL. D26—13)

To all whom it may concern:

Be it known that I, Chauncey E. Waltman, a citizen of the United States, residing at Chicago, in the county of Cook and State of Illinois, have invented a new, original, and ornamental Design for a Push Button, of which the following is a specification, reference being had to the accompanying drawing, forming a part thereof.

Figure 1 is a front elevational view of a push button, showing my new design.

Figure 2 is a side elevation further illustrating the same.

Figure 3 is a perspective view further illustrating the design features of the push button.

I claim:

The ornamental design for a push button, substantially as shown.

CHAUNCEY E. WALTMAN.
